(57) **CLAIM**

The ornamental design for a recreational board support, as shown and described.

DESCRIPTION

FIG. 1 is a perspective view of a recreational board support; FIG. 2 is a front view of the recreational board support; FIG. 3 is a right side view of the recreational board support; FIG. 4 is a left side view of the recreational board support; FIG. 5 is a back view of the recreational board support; FIG. 6 is a top view of the recreational board support; and, FIG. 7 is a bottom view of the recreational board support. The broken lines shown in the drawings are included for the purpose of illustrating environmental structure and form no part of the claimed design.
